LADDER

John W. Pease, Rochester, N. Y.

Application July 22, 1942, Serial No. 451,887

4 Claims. (Cl. 223—59)

My present invention relates to ladders and it has for its object to provide an inexpensive, simple and efficient means for fortifying the connections of the rungs, steps or treads thereof with the side rails, whereby loosening of the former and resulting weaving of the ladder structure as a whole will be obviated throughout the normal useful life of such a product. More particularly, the invention is concerned with a provision whereby in the hand assembly of ladders the said rungs, steps or treads will be squeezed or clamped with great force between the side rails rendering these parts relatively immovable for a long period and all without the use of any special assembling apparatus. In accomplishing this, my invention contemplates employing a combination strut and tie which, during fabrication, is automatically mutilated when it is tightened in a way that locks it in its ultimate position under stresses that preclude the possibility of it resuming the state in which it was applied.

To these and other ends, the invention resides in certain improvements and combination of parts, all as will be hereinafter more fully described, the novel features being pointed out in the claims at the end of this specification.

In the drawing:

Figure 1 is a side elevation of a step ladder constructed in accordance with and illustrating one embodiment of my invention;

Figure 2 is a front view thereof;

Figure 3 is an enlarged fragmentary vertical section taken in a plane extending longitudinally of one of the steps or treads and substantially longitudinally of the supporting side rails;

Figure 4 is a further enlarged fragmentary detail of the showing of Figure 3 with the parts in further section;

Figure 5 is a detail fragmentary section similar to Figure 4 taken on the line 5—5 of Figure 4 and

Figure 6 is a bottom plan view of the detail of Figures 4 and 5.

Similar reference numerals throughout the several views indicate the same parts.

I have shown and will describe my invention for the purpose of this application as applied to the construction of a step ladder in which connection I believe it to be most useful, because step ladders are self supporting at the upper ends as well as at the lower ends and are, therefore, subjected to greater strain conducive to loosening and weaving than are straight ladders that are leaned against a firm support, but the broader features of my invention are applicable to most

types of ladders. The accepted practice in the making of step ladders is to confine and support flat and rectangular steps or treads between side rails in which their ends are mortised or supported by cleats on the inside of the rails. The treads thus resist compression of the rails but it is important to find a fastening means to resist tendencies of the rails to spread and destroy tight contact with the tread ends. Once this looseness develops and the ladder starts to weave, it fractures the structure of the fibres of both wooden elements and gradually destroys their fit so that the condition grows progressively worse. In the practice of my invention I accurately fit the squared ends of the treads in square mortises in the rails and then hold them pressed together so tightly that relative movement and the tendency to weave is stopped before it starts.

Referring more particularly to the drawing, there is there illustrated a conventional folding type of step ladder comprising the ladder proper A, brace B hinged thereto at D with an appropriate fitting including the top C and intermediate folding braces E pivoted to both elements. The interior faces of the side rails 1 of the ladder proper A have straight shallow mortises 2 receiving the square ends of the flat treads 3. For preliminary assembly purposes the treads are fixed in position by nails 4 which also permanently serve to further prevent the treads from slipping longitudinally of the mortises although, as will hereinafter appear, they are hardly necessary for this purpose. A short distance below each tread 3 I bore the side rails 1 at 5 and insert therethrough a straight, or substantially straight, steel rod 6 the original condition and position of which is indicated by dotted lines in Figure 3. These are in the nature of bolts. The head 7 thereof at one end in each instance is provided with a washer 8 that bears against the outer face of one side rail while a nut 9 at the other threaded end through a similar washer 10 bears against the outer face of the other side rail. The rod or bolt is secured in this position with reasonable tightness according to the distance of the bores 5 from the underside of the tread.

The rod is first run through an eye in the flattened head 11 of a bolt 12, the threaded shank of which extends vertically through a hole in the center of the tread, which hole is counter-bored at 13 from above to accommodate a washer 14 beneath a nut 15. The bolt is also provided on the underside of the tread with a washer 16 engaged by the shoulder of the head 11 as shown

in dotted lines in Figure 3. The shank of the bolt 12 is originally longer than is shown by full lines in the drawing to permit the insertion of the washer 14 and the nut 15 thereon in the counterbore 13. As the nut is tightened it bends the rod 6 upwardly at the center until the washer 16 is compressed between it and the underside of the tread 3. Not only this, but the tightening of the nut is continued until a portion of the rod is locally further distorted and actually drawn into the opening 17 in washer 16. This opening is considerably larger than the bolt head and its inner margins are preferably left with sharp corners or burrs which, with the pressure generated by the nut, actually cut into or dent the rod. Between such abutments, the portion of the rod that is within the bolt head and immediately adjacent thereto is swedged into the washer opening as indicated at 18 in Figures 4 and 5. The rod can thereafter not slide relatively to the tread and its fittings in either direction and each half thereof is placed under tension independently of the other to form a tie piece between the center of the tread and one of the side rails. In fact, either such tie section could be severed without greatly disturbing this function in the other. The edges or corners of the hole in the flat bolt head 11 are left as sharp as possible also so that they cut into the underside of the rod 6 to maintain this tensile strain.

Finally the projecting threaded ends of the bolt 12 are sheared off level with the upper surfaces of the tread and are preferably upset or riveted over on the nuts 15 to lock them against loosening.

The fibres in the internal structure of the connected wood parts 1 and 3 are, of course, slightly compressible, but they also react with a corresponding sustained expansive force that holds all of the material connections in extremely tight contact where the original compressive force of the rod and bolt action is exerted. Such is the case in the matter of the grain ends of the treads crowding the mortises of the rails and with the treads acting as struts and the rods themselves acting as practically independent ties, a triangulation of forces is created that prevents the treads from even starting to loosen and hence holds the ladder as a whole rigidly against the weaving first mentioned in this application.

I claim as my invention:

1. In a ladder, the combination with a pair of side rails and an abutting tread therebetween having its ends supported thereby and acting as a strut, of a tie rod extending through both side rails below the tread to react compressibly at its ends against the outer faces thereof at points below the tread, and means on the tread for forcibly laterally distorting the rod intermediate its length, the engagement of said means with the rod being adapted to prevent the relative movement of each in a direction longitudinally of the rod.
2. In a ladder, the combination with a pair of side rails and an abutting tread therebetween having its ends supported thereby and acting as a strut, of a tie rod extending through both side rails below the tread to react compressibly at its ends against the outer faces thereof at points below the tread, an intermediate portion of the rod being distorted upwardly adjacent to the underface of the tread, and a fixed eye on the underside of the latter locked with the said distorted portion of the rod to tension and prevent endwise movement of the latter.
3. In a ladder, the combination with a pair of side rails and an abutting tread therebetween having its ends supported thereby and acting as a strut, of a tie rod extending through both side rails below the tread to react compressibly at its ends against the outer faces thereof at points below the tread, a washer on the underside of the tread, an intermediate portion of the rod being distorted upwardly to occupy the opening in the washer, a bolt extending through the tread having a head smaller than the washer opening provided with an eye engaging the distorted portion of the rod, and a nut on the upper side of the tread threaded on the bolt.
4. In a ladder, the combination with a pair of side rails and an abutting tread therebetween having its ends supported thereby and acting as a strut, of a tie rod extending through both side rails below the tread to react compressibly at its ends against the outer faces thereof at points below the tread, incompressible means on the underside of the tread having two points of engagement with an intermediate portion of the rod and a rod distorting means on the tread engaging the rod between said points of engagement.

JOHN W. PEASE.
